UNITED STATES PATENT OFFICE.

HERMAN P. ROBINSON, OF BRISTOL, TENNESSEE.

STEAM CHEST AND BALANCE SLIDE VALVE THEREFOR.

Application filed June 22, 1920. Serial No. 390,803.

To all whom it may concern:

Be it known that I, HERMAN P. ROBINSON, a citizen of the United States, residing at Bristol, in the county of Sullivan, State of Tennessee, have invented a new and useful Steam Chest and Balance Slide Valve Therefor; and I do hereby declare the following to be a full, clear, and exact description of the invention, such as will enable others skilled in the art to which it appertains to make and use the same.

This invention relates to the art of steam engineering, and more particularly to an improved steam valve chest and balance slide valve therefor.

Heretofore steam chests have been constructed with their cover or top plates removable, which it has been found renders it very inconvenient to attain ready access to the interior of the steam chest, and the slide valve therein, and also making it very difficult to remove the slide valve and its rod, for inspection and repairs. Furthermore this form of construction prevents a mechanic from readily readjusting the valve in the chest, with relation to its rod and the gearing of the rod, when replacing the valve after inspection and making other repairs. Furthermore, in this form of construction it has been found inconvenient to rearrange the spring tensioned steam packing strips or member particularly when replacing the cover or top plate, owing to the packing strips or members tending to become displaced before the cover or top plate is finally secured in position.

Consequently the present invention aims as its foremost object to overcome these disadvantages or difficulties, by providing an improved steam chest for balance slide valves, in which either head of the chest is readily removable or detachable, thereby permitting ready accessibility to the valve.

A further object of the invention is to provide a steam valve chest, having one or both of the heads easily removable from the chest, and should it be the head having the stuffing box, it may be slid back on the valve rod, and the rod subsequently detached from the valve gear, after which the valve and the rod may be easily removed, so that it can be easily inspected and also subjected to any necessary machine work or other repairs.

A further object of the invention is to provide a device of this kind, in which the

slide valve is readily removable as aforesaid thereby permitting ready access to the steam chest, whereby it may be inspected, and repairs easily made.

A further object of the invention is to provide a steam valve chest, in which either one or both of the heads are removable, so that when replacing the valve, it may be accomplished with ease, without any interference from the spring tensioned steam packing ring or member, since they may be easily held in place while sliding the valve into the chest. In other words, in replacing the valve after the repairs have been made, the packing ring or members may be readily adjusted into place.

A further object of the invention is to provide a device of this kind, so that when replacing the valve, its rod may be easily and quickly reconnected to the valve gear.

A further object of the invention is the provision of a steam valve chest, in which either one or both of its heads are removable; one head carrying a stuffing box for the valve rod, the neck ring of which acts as a bearing, the other head carrying a relief valve, also a bearing for the extension valve rod. This valve may be used either with or without this extension valve rod or front bearing.

In practical fields the details of construction may necessitate alterations falling within the scope of what is claimed.

The invention comprises further features and combination of parts as hereinafter set forth, shown in the drawings and claims.

In the drawings:—

Figure 1 is a view in perspective of an improved steam chest for balance slide valves constructed in accordance with the invention, showing the same mounted upon the steam cylinder.

Figure 2 is a longitudinal sectional view on line 2—2 of Figure 1, showing the piston and the valve of the steam cylinder and steam chest respectively in elevation.

Figure 3 is a plain view of the steam chest showing the same mounted on the steam cylinder.

Figure 4 is a cross sectional view on line 4—4 of Figure 3.

Figure 5 is a detail perspective view of one of the heads of the steam chest.

Figure 6 is a detail view of the balance slide valve.

Referring more specially to the drawings, 1 designates a conventional form of steam

cylinder, in which the usual construction of piston 2 reciprocates. The piston 2 has its piston rod 3 operating through the usual stuffing box 4, and may be connected in the usual manner, not shown, to the engine wheel, not shown, for imparting revoluble movement thereto. The cylinder 1 has rising upwardly therefrom the usual enlargement or body 5, on which the improved steam chest 6 is mounted. This steam chest comprises the improved hood casing 7^a, which is substantially semi-cylindrical, and is provided with longitudinally extending side flanges 8. The side flanges 8 extend laterally, and are fastened or secured to enlargement 5 by stud bolts 9 which pass through spacer 11. Where the edges of the hood casing 7^a are secured, they are seated on copper joints 12. The top of the hood casing is provided with a longitudinally extending portion 13, in which is formed an oil duct 14, having its end branches 15 merging to and in communication with the interior 16 of the steam chest, and by means of the connection 17 any suitable or conventional oil cup, not shown, may be connected in order to supply oil to said duct. Secured by the bolts 18 (which are threaded into the end edges of the hood casing) the steam chest head or end plates 19 and 20 are secured to the hood casing. The end plate or head 19 at its lower part adjacent the side edges is provided with laterally extending ears or lugs 21, bolts 22 extend through lugs 21 and spacer 11 and into the enlargement 5, thereby assisting and holding said head or plate 19 in place. Where the ears or lugs 21 are secured, they engage the recess 23. Projecting laterally from the head 19 is a flange 24 having openings 25. Also formed upon the outer face of the head 19 is one section or part 26 of a stuffing box, which is preferably of the shape shown, and passing through the opening 25 of the flange 24 are suitable stud bolts 27, which pass through spacer 11 and are threaded into enlargement 5, thereby holding the head 19 secure. By virtue of the section or portion 26 of the stuffing box being rectangular and the stud bolts engaging on either side thereof, the head 19 is rendered more secure. The head 20 of the steam chest has its lower portion provided with a lateral flange 28, which also engages a recess 29 of the spacer 11 of the enlargement 5, there being bolts 30 passing downwardly through the flange 28, so as to secure the head 20 in position. It is to be noted that the hood casing and the two heads practically fit down over an auxiliary raised portion 31 of the spacer 11, which also insures security of the steam chest. Formed through the enlargement 5 and communicating the interior 16 of the steam chest with the interior of the cylinder are the usual steam ducts 32 and 33. Also formed in the

enlargement 5 is a steam intake passage 34, the inner portion of which at both ends is provided with upwardly extending ports 35, whereby steam may enter the steam chest on either end of the slide balance valve. Also formed in the enlargement 5 is an exhaust port 36, the inner angular end of which communicates with interior of the steam chest, between the end portion of the slide balance valve, thereby permitting the exhaust of utilized steam. The other member 24^a of the stuffing box is received into the part 26, there being the usual packing 38, and passing through this packing box or gland the usual form of valve rod 39 reciprocates. Mounted upon the valve rod and secured thereto in any suitable manner as shown at 40 is a balance slide valve 41, substantially similar to the one illustrated, set forth, and claimed in a former patent to H. P. Robinson, Patent No. 1,140,188, on which the present invention is a vast improvement. However, this balance slide valve comprises the semi-circular end heads 42 and the connecting bars or parts 43, which integrally connect the lower side edges of said valve head 41 and 42. The edges of the heads 42 which wipe adjacent the inner circumference of the hood casing are channelled as shown at 44, to receive the usual spring tensioned steam packing rings or members 45, which are similar to the packing rings in the aforesaid patent. The outer faces of the connecting bars or members 43 are also channelled, to receive spring tensioned steam packing members 46, which members and those aforesaid are designed to prevent the escape of steam from the spaces adjacent the end faces of the valve heads, to the steam exhaust cavity 47, which is between said valve heads. By virtue of the stuffing box a bearing for the valve rod is assured, to prevent excessive lifting of the valve from its seat face 48 of the raised part 31. Furthermore, by means of the first mentioned steam packing members the lower face of the slide balance valve is held in close contact with its seat. Preferably one end of the valve rod 39 is extended as shown at 49, and this extension is mounted in a bearing 50 of the tubular portion 51, which connects the usual steam relief valve 52 to the head 20 of the steam chest. This tubular portion 51 is threaded into the head 20, and may be removed when desired, for repairing the relief valve. The extension 49 of the valve rod may be dispensed with if so desired. In the operation, steam passes through the port or passage 34 into the steam chest through the ports 35 and between the heads of the balance slide valve and the heads of the steam chest. As shown in Figure 2, the piston 2 is moving in the direction of the arrow a, and consequently the slide valve has uncovered the duct 33, allowing steam to act

upon the face *b* of the piston, while the steam between the other face of the piston and one end of the cylinder is exhausting out through the duct 32, into the exhaust cavity 47, and finally out through the duct 36. When the slide valve is in the act of throwing the port or duct 33 in communication with the exhaust cavity 47 of the slide valve, the duct 32 is being thrown into communication with the steam space between the valve head 41 and the steam chest head 19, whereby the steam may act upon the face *c* of said piston 2, consequently move the piston in the reverse direction to the arrow *a*. By virtue of the extension 49 operating in its bearing 50, together with the neck ring bearing of the stuffing box, the valve rod 39 is caused to move in a straight line which greatly reduces the tendency to cock the valve or lift it from its seat.

The invention having been set forth what is claimed as new and useful is:—

1. In a steam chest for balance slide valves, a base having a raised rectangular shaped valve seat, a hood casing semicircular in cross section arching said seat and engaging the opposite sides of the raised rectangular shaped valve seat, longitudinally disposed flanges carried by the hood casing and spaced from the side edges thereof, bolts passing through said flanges and extending into the base, semi-circular heads for said hood casing, said heads engaging the ends of the raised portion forming the valve seat, bolts passing through said heads and into the ends of the hood casing, one of said heads being provided with a stuffing box for the reception of the valve rod, a transversely disposed flange carried by said last named head and disposed above the stuffing box, bolts passing through said flange and into the base and located adjacent the sides of the stuffing box, lugs carried by said head

adjacent its lower outer corners and engaging the valve seat base, and bolts passing through said lugs and into the base.

2. In a steam chest for balance valves, a base having a raised valve seat, a hood casing semi-circular in cross section arching said valve seat and engaging the sides of the raised portion forming the valve seat, a slide valve disposed within the hood casing, removable heads secured to the ends of the hood casing and engaging the end walls of the raised portion forming the valve seat, flanges carried by the hood and spaced from the lower edges thereof, bolts passing through said flanges and into the base, one of said heads being provided with a stuffing box for the reception of the valve stem, a flange carried by said last named head and disposed above the stuffing box, bolts passing through said flange and into the base adjacent the stuffing box, lugs carried by the outer corners of said head and engaging the base, and bolts passing through said lugs into the base.

3. The combination with a slide valve disposed on a raised valve seat, said slide valve being carried by a horizontally disposed valve rod, of a removable steam chest therefore, said removable steam chest comprising a semi-circular member arching the slide valve and secured to opposite sides of the valve seat, removable semi-circular heads for said steam chest and slidably mounted on the valve stem, said heads being detachably connected with the ends of the semi-circular member and to the valve seat.

In testimony whereof I have signed my name to this specification in the presence of two subscribing witnesses.
